ATTY

UNITED STATES PATENT OFFICE.

EDWARD W. WEILAND, OF FRESNO, CALIFORNIA.

DOOR LATCH AND BUMPER.

1,300,530.

Specification of Letters Patent. Patented Apr. 15, 1919.

Application filed December 5, 1917. Serial No. 205,499.

To all whom it may concern:

Be it known that I, EDWARD W. WEILAND, a citizen of the United States, residing at Fresno, in the county of Fresno and State 5 of California, have invented new and useful Improvements in Door Latches and Bumpers, of which the following is a specification.

The present invention relates to improvements in latches for screen doors.

10 The object of the invention is to provide in a screen door which can be closed by means of spring hinges, means for preventing the slamming of the door, and means for latching the door either when it is quite 15 closed or when, owing to such preventive means, it is not quite closed but closed sufficiently to exclude the flies.

20 A further object is to provide a device of this character which can be installed very easily and cheaply and without employing skilled labor for the purpose.

25 In the accompanying drawing, Figure 1 is a broken horizontal section of a door and the jamb therefor, showing my improved latch and bumper in plan view in one position thereof; Fig. 2 is a similar view showing the same in another position; Fig. 3 is a broken sectional view of the door, showing the latch in bottom plan view; Fig. 4 is a 30 horizontal longitudinal section through the latch; Fig. 5 is a broken side view of the door showing a latch and bumper thereon; Fig. 6 is a broken perspective view of the latch detached; Fig. 7 is a perspective view 35 of the bottom of the casing detached; Fig. 8 is a similar view of a striking plate; Fig. 9 is a similar view of a lock.

40 Referring to the drawing, 1 indicates the jamb of a door 2, having its outer edge rabbed, as shown at 3, to receive the free vertical edge of the door. To said jamb is secured a striking plate 4, having a portion nearest the door rounded, as shown at 5, to receive the impact of a striking plate and 45 having a vertical edge 6 adapted to engage a latch 7 of the door to hold it closed. 8 indicates a latch casing of sheet metal, the central portion 9 of which is of an arch-shaped form and which has flanges 10 attached by 50 screws 11 to the door 1. The latch casing 8 forms the principal member of a guideway for a latch, the remainder of the guideway being formed by a bottom 13, also formed of sheet metal, and secured within the arch-shaped portion of the latch casing by means 55 of lugs 14 extending out therefrom and

through pairs of slots 15, 16, in opposite sides of the latch casing, the hole 15 being longer than the holes 16 to enable the lugs 14 to be inserted therethrough from the inside of the casing, said lugs extending downward against the walls of the latch casing to hold the casing from spreading, should the screw 11 be improperly inserted and not hold firmly in the door.

60 The latch 7 which slides within the latch casing is formed of two sections 17, 18, of sheet metal, forming the respective sides of the latch, and having extensions 19, which are riveted together, as shown at 20, and 65 have beveled advancing edges 21 adapted to impinge against the rounded portion 5 of the striking plate as the door closes. Said extensions 19 can slide in an open-ended slot 25 in the middle of the front end of the latch 70 casing 8. The front end of the horizontal portion of each section is formed with an angular recess 22, said recesses constituting 75 a hook adapted to engage the free vertical edge 6 of a striking plate to cause said latch 80 to be retained by said striking plate when the door is nearly closed. The inner edges of the horizontal portions of said sections 85 constitute in effect another hook 23 to engage said free edge to retain the door when it is closed tight.

To withdraw the latch, the edge of the upper one 17 of said sections adjacent to the other section is recessed, as shown at 24, through which, and through slots 26, 27, in 90 the bottom 13 and casing 8 respectively, extends a latch lever 28, which can also abut against a lug 48 bent up from the upper section at the rear end of said recess. Said latch lever 28 also extends through a hole 95 29 in the door, and through a hole 31 in a plate 32, the ends of which are secured by screws 33 to the outer side of the door, said plate being bent to form a pull adapted to be engaged by a finger to open the door from 100 the outside.

The slot or recess 24 for the latch lever is located at one side thereof in order to make room for a coiled spring 34, of which the rear end is secured to a lug 35 cut out and 105 bent from the latch, while the other end is secured to a hole in the front end of the bottom 13. This spring always returns the latch to its locking position when released from the lever.

110 Said latch lever is formed of a single long and narrow piece of metal folded along a

longitudinal central line, and bent into a hooked shaped form at its inner end 36. The outer terminal portion is reduced in diameter to provide a shoulder 37, and the 5 outermost portion is wider than the remainder in order to provide flanges 38 which are bent outwardly at right angles to the remainder of the metal to prevent the lever being withdrawn through the hole 31 in one 10 direction, and also to provide a wide surface for thumb pressure, while the shoulder 37 limits the movement in the other direction of said lever.

When it is desired to lock the latch in a 15 position retaining the door closed, there is provided a lock 39 having a shorter leg 40 and a longer leg 41, and bent over at its upper end, as shown at 42, to provide a finger piece. Said legs 40, 41, slide through holes 20 in the upper side of the arch-shaped portion of the latch guide close to the upper flange, and the longer leg 41 also slides through a hole close to the lower flange in the lower side of said arch-shaped position, and is 25 then bent outwardly, as shown at 45, to retain the lock in place. Said longer leg guides the lock in its vertical reciprocating movement. When the lock is pushed in, however, the shorter leg 40 then extends immediately to the rear of the latch lever when 30 in its forward or locking position, so that said lever cannot be drawn back to withdraw the latch from its locking position.

The holes in the upper side of the arch-shaped casing through which the legs 40, 41, pass are spaced from each other at such a distance relative to the distance between the legs 40, 41, that, when the lock is pushed outward, said legs are pressed toward each 40 other, the friction thereby caused tending to retain the lock in its upper or inoperative position against gravity.

There is also provided a bumper 43 of rubber, secured to the free end of an arm 44 pivoted by a screw 46 on the door immediately above the latch casing, so that, when the bumper arm 44 is in one position, a lug 49 extending from the lower edge of said arm abuts against the upper side of the upper flange 10 of said casing, and said bumper is then in a position intervening between the jamb and the door when the latter is closed. When the upper arm is moved in the opposite direction a lug 50 extending 55 from its other longitudinal edge rests upon said flange and the bumper then no longer

thus intervenes and is inoperative. A washer 47 intervenes between the arm 44 and the door to prevent the arm 44 wearing against the door.

The bumper 43 is attached to the arm 44 by a screw 48, so that, when worn out, it can readily be replaced by a new one.

It will be observed that but one rivet is employed, namely, the rivet 20, and that otherwise the device is made wholly of sheet metal bent to the proper form, and can be attached in place with the greatest ease.

I claim:

1. In combination with a door and a jamb therefor, a bumper attached to one of said elements so as to be movable into positions in which it is respectively operative and inoperative to resiliently resist the closing motion of the door, a striking plate on the jamb, and an automatic latch on the door for engaging said striking plate, one of said co-engaging elements being provided with means for engaging the other in either of two latching positions corresponding to the operative and inoperative positions of the bumper.

2. In combination with a door, a latch casing secured thereto, a latch slidable in said casing, a latch lever for operating said latch, and a lock for locking said latch lever having a bent portion forming a finger piece, a long guide leg extending through holes in the walls of the latch casing, and a short locking leg extending through a hole in one wall thereof, said short leg being adapted to move immediately to the rear of said latch lever in its locking position to maintain it locked.

3. In combination with a door, a latch casing secured thereto, a latch slidable in said casing, a latch lever for operating said latch, and a lock for locking said latch lever having a bent portion forming a finger piece, a long guide leg extending through holes in the walls of the latch casing, and a short locking leg extending through a hole in one wall thereof, said short leg being adapted to move immediately to the rear of said latch lever in its locking position to maintain it locked, the distance between said holes being slightly different from that between the legs whereby when the legs are moved transversely they are engaged by sides of said holes with a frictional engagement and retained thereby.

EDWARD W. WEILAND.
